UNITED STATES PATENT OFFICE

154,542

DESIGN FOR AN ELECTRIC SCALP BRUSH OR THE LIKE

Orville S. Hershey, Evanston, Ill., assignor to Hershey Mfg. Co., Chicago, Ill., a corporation of Illinois

Application December 27, 1948, Serial No. 150,389

Term of patent 14 years

(Cl. D9—2)

To all whom it may concern:

Be it known that I, Orville S. Hershey, a citizen of the United States, residing at Evanston, in the county of Cook and State of Illinois, have invented a new, original, and ornamental Design for an Electric Scalp Brush or the like, of which the following is a specification, reference being had to the accompanying drawing, forming part thereof, wherein—

Fig. 2 is a top plan view thereof;

Fig. 3 is an elevation of the brush end which appears at the left in Fig. 2; and

Fig. 4 is an end elevation of the opposite end thereof.

The dominant features of my design reside in those portions shown in full lines.

I claim:

The ornamental design for an electric scalp brush or the like, as shown and described.

ORVILLE S. HERSHHEY.
